UNITED STATES PATENT OFFICE.

JOHN LEWIS SHOEMAKER, OF CRANDON, WISCONSIN.

NON-REFILLABLE BOTTLE.

1,282,303.

Specification of Letters Patent. Patented Oct. 22, 1918.

Application filed February 9, 1916. Serial No. 77,198.

To all whom it may concern:

Be it known that I, JOHN L. SHOEMAKER, a citizen of the United States, residing at Crandon, in the county of Forest and State 5 of Wisconsin, have invented certain new and useful Improvements in Non-Refillable Bottles, of which the following is a specification.

This invention relates to bottles and pertains more particularly to nonrefillable. 10 bottles.

The principal object of this invention is to provide an attachment adapted to be applied to the neck of the bottle after the same has been filled, which will permit only 15 the free outward passage of the contents of the bottle and one which will be simple and cheap to manufacture and capable of being made of a suitable material which will not injure the contents of the bottle and can 20 be applied to bottles not differing essentially from the bottles in common use.

With these and other objects in view this invention consists in the construction, combination and arrangement of parts as will 25 be hereinafter described and claimed.

Reference is to be had to the accompanying drawings forming part of this specification, in which similar reference characters designate corresponding parts throughout 30 the several views, and in which—

Figure 1 is a fragmentary view in section of a bottle showing my invention applied,

Fig. 2 is a similar view showing the bottle inverted,

Fig. 3 is a perspective view of the guard retaining means,

Fig. 4 is a perspective view of the guard, and

Fig. 5 is a perspective view of the valve.

Referring more particularly to the drawings in which is shown the preferred embodiment of my invention, 1 designates the bottle with a neck 2 in which is mounted a glass stopper 3. The neck of the bottle 45 where it joins the body is enlarged and provided with a concave upper surface 4, the purpose of which will be hereinafter more fully set forth.

The stopper 3 is provided with a central bore 5 in which is slidably mounted the valve guard 6. The guard is provided adjacent its lower extremity with a circumferential groove or recess 7, as will be more fully seen in Fig. 4, into which is arranged 55 a split retaining ring 8, which may be composed of any suitable material that will not

injure the contents of the bottle, such as cork, glass or rubber. The ring 8 is of approximately the same diameter as the interior of the bottle neck prohibiting the 60 insertion of a tool or wire to unseat a valve in order to refill the bottle.

The guard 6 is provided with a central bore 9 through which the liquid finds passage upon inverting the bottle. Slots 10 65 opening into the bore 9 are formed in the lower end of the guard allowing the liquid to enter the bore. A stopper of the common type may be utilized in closing the bore through the guard when the bottle is not in 70 use. The lower end of the guard is hollowed out to permit of its being firmly seated on the valve.

In order to close the entrance to the bottle body to prevent filling of the same after 75 once sealed, a ball valve 11 is placed in the neck so that it will be seated on the portion 4 of the neck when the bottle is in an upright position.

In assembling this device, after the bottle 80 has been filled the valve is inserted, then the ring 8 is placed in the recess 7 of the guard 6, which is then placed in the neck of the bottle so that the hollowed out portion will be seated on the valve. When this is done 85 the glass stopper 3 is secured in the neck by applying cement or other adhesive which renders it impossible to remove the stopper without mutilating it or the bottle.

It will be seen by referring to Fig. 2 that 90 when the bottle is tilted to withdraw the contents, the guard slides through the stopper until the ring comes into contact with the stopper, which securely holds the guard from complete extraction. In this position 95 the ball valve is free to move from its seat, permitting free flow of the liquid around the valve through the slots 10 and bore 9 to a receiving receptacle. Immediately upon righting the bottle, the valve will be reseated 100 tightly on the portion 4 prohibiting the entrance of any liquid to the bottle. As above stated the ring 8 prevents a tool being inserted in the neck to lift the valve.

Various changes in the form, proportion 105 and minor details of construction, may be resorted to without departing from the principle or sacrificing any of the advantages of this invention as claimed.

What I claim as new and desire to secure 110 by Letters Patent, is:—

The combination with a bottle neck hav-

ing a straight interior wall and being enlarged at its juncture with the bottle and provided with a concave upper surface forming a valve seat, of a stopper, having a 5 central bore, fixedly secured in the bottle neck, a valve, a valve guard slidably mounted in the stopper bore, said guard having a longitudinal bore communicating with ports arranged at one end of the guard, 10 the guard being further provided with a circumferential groove adjacent the end provided with the ports, the upper terminal

of the groove being in alinement with the under surface of the stopper, and a split ring having a diameter equal to the interior 15 diameter of the bottle neck, said ring being slidably mounted in the groove and freely slideable in the bottle neck.

In testimony whereof I affix my signature in presence of two witnesses.

JOHN LEWIS SHOEMAKER.
